UNITED STATES PATENT OFFICE

172,763

LAMINATED PLASTIC SHEET

George C. Rassman, Coshocton, Ohio, assignor
to General Electric Company, a corporation of
New York

Application May 27, 1953, Serial No. 25,208

Term of patent 14 years

(Cl. D87—3)

To all whom it may concern:

Be it known that I, George C. Rassman, a citizen of the United States, residing at Coshocton, in the county of Coshocton, State of Ohio, have invented a new, original, and ornamental Design for a Laminated Plastic Sheet, of which the following is a specification, reference being had to the accompanying drawing, forming a part thereof.

The drawing is a plan view of the laminated plastic sheet embodying my new design.

A design unit is shown within the broken lines and is repeated as indicated.

I claim:

The ornamental design for a laminated plastic sheet, as shown and described.
